UNITED STATES PATENT OFFICE

152,606

DESIGN FOR BABY PANTIES

Esther Foreman, Evansville, Ind.

Application February 4, 1948, Serial No. 144,272

Term of patent 3½ years

(Cl. D3—17)

To all whom it may concern:

Be it known that I, Esther Foreman, a citizen of the United States, residing at Evansville, Indiana, have invented a new, original, and ornamental Design for Baby Panties, of which the following is a specification, reference being had to the accompanying drawing, constituting a part thereof.

Fig. 1 is a front view of the panties, showing my new design;

Fig. 2 is a side view of the same;

Fig. 3 is a rear view of the same;

Fig. 4 is a view showing the panties in flat position from the inside; and

Fig. 5 is a view similar to Fig. 4 from the outside.

I claim:

The ornamental design for baby panties, substantially as shown.

ESTHER FOREMAN.
